BURGLARPROOF WINDOW SCREEN

John B. Bollinger, San Francisco, Calif.

Application February 1, 1935, Serial No. 4,547

3 Claims. (Cl. 20—71)

The present invention relates to improvements in burglar-proof window screens and has particular reference to sash windows.

The principal object of the invention is to provide a window screen that is actuated by sash movements so as to cover the space left free by a sash opening movement and to automatically retract or collapse on a sash closing movement which causes the space occupied by the window to be covered at all times, either by the sash itself or by the screen.

A further object of the invention is to provide a screen of the character described which is very rigid and strong in construction, particularly for the lower sash so as to make it difficult for a burglar to break the same or to tamper with it for the purpose of gaining access to the house through the open window.

A further object of the invention is to provide a screen of the character described which allows of a certain degree of draft regulation by imparting a desired direction to the outside air entering through the screen.

Further objects and advantages of my invention will appear as the specification proceeds. It should be noted that in the drawing I show two forms, which may be used singly or in combination or which may be substituted one for the other, although I prefer to use the two forms, each in its place, one being better adapted to be used in connection with the lower sash of a double sash window and the other being better adapted to be used in connection with the upper sash.

The two forms of my invention are illustrated in the accompanying drawing, in which

Figure 1 shows a front view of a double sash window having my two screens attached thereto, the upper sash being partly open;

Figure 2 a central vertical section through the window shown in Figure 1;

Figure 3 a front view of the same window, with the upper sash closed and the lower sash partly open;

Figure 4 a central vertical section through the window shown in Figure 3, and

Figure 5 an enlarged detail view of the lower portion of the section shown in Figure 4.

While I have shown only the preferred forms of my invention I wish to have it understood that various changes and modifications may be made within the scope of the claims hereto attached without departing from the spirit of the invention.

Referring to the drawing in detail it will be

noted that the window 1 is substantially of standard construction and includes the frame 2 and the two sashes 3 and 4 slidable therein with freedom of vertical movement in overlapping relation. Suitable weights (not shown) may be provided in a conventional manner for causing the sashes to remain automatically in any position to which they have been adjusted.

Each of the sashes has its own screen associated therewith, the lower screen being shown at 5 and the upper screen being shown at 6. The lower screen is made somewhat more substantial than the upper screen, because the danger of a burglar trying to break in through the lower screen is greater. It is also constructed differently to allow of a certain amount of draft regulation.

The lower screen comprises a plurality of horizontal plates 7 arranged in edge to edge relation so as to form a continuous series of plates which are hinged together along the contiguous edges thereof. The lowermost of the plates is hinged to a stationary plate 8 secured on the window sill 9 and the uppermost is hinged to a plate 10 secured to the bottom member 11 of the lower sash, a thin strip of wood 12 being preferably interposed, the strip running between the vertical guides 13 secured to the frame. The hinges are preferably arranged with the hinge pins alternately on different sides of the plates, whereby a slight angularity is maintained even in the most extended position of the screen. It will be noted that in the drawing four different plates are shown, with a central hinge pin 14, which is disposed on the outside of the two plates connected thereby and which rides in vertical slots 15 provided in the window frame so as to be confined to a vertical path. The other two hinge pins 16 are disposed on the inside of each set of plates connected thereby so that even if the three hinge pins were perfectly aligned in the most extended position of the screen, the plates would still maintain a slight angularity to one another which is required for the initial collapsing movement. The pins 16 cannot swing inwardly beyond the vertical plane of pin 14 because they are prevented from doing so by the upright guides 13 fastened to the sash.

The plates are perforated to allow of the entrance of air therethrough and the perforations are preferably punched into the plates from the inside so as to leave a roughened outer surface with sharp projecting points to make it more difficult to tamper with the screen from the outside. Suitable handles 18 are provided on the

lower sash member to allow the sash to be raised conveniently and these handles are preferably provided with spring extensions 19 bearing down on the uppermost plate when the screen is collapsed.

The operation of the lower screen will be readily understood from the foregoing description. As the lower sash is raised the plates which normally lie one on the other as shown in Figure 2, 10 are raised with the sash in zig-zag relation to assume the position indicated in Figure 5, the hinge pin 14 being confined to a vertical path while the other hinge pins are gradually drawn toward the sash as the assembly straightens out. The 15 plates are prevented from straightening out completely into a vertical plane by the peculiar hinge arrangement so that when the sash is lowered again the plate assembly will automatically collapse into the position indicated in Figure 2, the 20 spring 18 aiding in bringing about a perfect collapse.

It will be noted due to the angular relationship of the plates the air passing through it is directed either upwardly or downwardly, whereby direct 25 draft is largely eliminated. The plates directing the draft downward may, of course, be left unperforated, if no downward draft is desired.

The upper screen 6 is in the nature of a conventional shade and comprises a conventional shade roller 21 with the well-known spring mechanism (not shown in the drawing), tending to 30 turn the roller in one direction and a wire screen 22 wound thereon, the lower edge of the wire screen being secured to the top member of the 35 upper sash as shown at 23. The screen is preferably made of a width to cover the entire window opening and should be made of rather elastic material, such as spring steel.

In this manner the raising of the lower sash 40 will automatically set in action the lower screen while the lowering of the upper sash will set in motion the upper screen, so that the window opening is covered at all times while both screens collapse automatically when the sashes are closed.

I claim:

1. A burglar-proof screen for a window having a frame and a sash slidable therein, comprising a plurality of perforated plates arranged in edge to edge relation to form a continuous assembly, hinge pins connecting the plates and means for connecting the end plates to the frame and the sash respectively whereby the assembly is made to expand and collapse in response to sash movements, the hinge pins being offset relative to the 10 plate assembly and being disposed alternately on opposite sides of the latter to facilitate the collapsing operation.

2. A burglar-proof screen for a window having a frame and a sash slidable therein, comprising 15 a plurality of plates arranged in edge to edge relation to form a continuous assembly, hinge pins connecting the plates, means for connecting the end plates to the frame and the sash respectively whereby the assembly is made to expand and collapse in response to sash movements and spring means secured relative to the 20 sash and bearing on the collapsed plate assembly for urging the plates thereof into close relation.

3. A burglar-proof screen for a window having a frame and a sash slidable therein, comprising a plurality of plates arranged in edge to edge relation to form a continuous assembly, hinge pins connecting the plates, means for connecting 30 the end plates to the frame and the sash respectively whereby the assembly is made to expand and collapse in response to sash movements, the hinge pins being offset relative to the plate assembly and being disposed alternately on opposite 35 sides of the latter to facilitate the collapsing operation and alternate hinge pins extending beyond the plates and having guide means for retaining the same in a plane adjacent the sash during the collapsing operation, and spring means secured 40 relative to the sash and bearing on the collapsed plate assembly for urging the plates thereof into close relation when collapsed.

JOHN B. BOLLINGER.
